SOUND AMPLIFIER

Filed June 24, 1925

Inventor
E. H. Hollinson
By his Attorney
Charles L. Wright

UNITED STATES PATENT OFFICE.

EARL H. ROLLINSON, OF LYONS FARMS, NEW JERSEY.

SOUND AMPLIFIER.

Application filed June 24, 1925. Serial No. 39,205.

This invention relates to sound amplifiers in which diaphragms are caused to vibrate by electro-magnetic or mechanical instrumentalities, and particularly to such devices as are used in connection with radio apparatus.

One object of the invention is to provide an ornamental support base of insulate material to which a horn may be attached, the base having a chamber to contain a telephone receiver unit of approved type.

A further feature is in the provision of a pair of diaphragms arranged in operative relation within the base and means whereby the diaphragms may be mutually adjusted therein to present an unusually agreeable resonant effect, which may be modulated to produce a variation in pitch.

Another aim is to provide a novel type of diaphragm contactor, reversibly mounted and having peculiar properties in connection with a companion diaphragm tending to augment and clarify the high or low pitched sounds emanating from the unit.

These and other relevant features are achieved by the present design and arrangement of elements hereinafter described and displayed in the associated illustrations, a constituent of this disclosure, and in which:

Figure 1 is a transverse sectional view of an amplifier support made in accordance with the invention, the section being taken on line 1—1 of Figure 2.

Figure 2 is a bottom plan view of the same, the base member being omitted.

Figure 3 is a top plan view thereof.

Figure 4 is a similar transverse sectional view showing a modified form of diaphragm contact.

Figure 5 is an enlarged fragmentary sectional view of the contactor as attached to the upper diaphragm.

The body 10 of the support is made of dielectric material, preferably that commercially known as bakelite, by molding in highly finished dies to produce a smooth surface, having the appearance of a polish finish.

In the upper contracted end of the body is an opening 11 leading to a chamber 12, and fitted to rotate in the opening is an annular flange 13 extending from a cap 14, having an imperforate cover portion 15, from which rises a central hub 16 reenforced by ribs 17.

The tapered portion of a conventional type of horn 18 is provided with a stop collar 19 to rest on the hub 16, and the straight cylindrical end 20 of the horn is closely fitted to the hub opening to extend level with the lower surface of the cover element 15, above the space 21 in the cap.

Fixed to the annularly shouldered portion 14 of the cap is a thin flat ring 22 extending outwardly over the upper portion of the body, and carrying a series of graduations 23 arranged in decimal sequence relative to an index mark 24 on the margin of the body, as can best be seen in Figure 3.

The inner surface of the cap flange 13 is screw-threaded and engaged therein is the flange 25 of a cup 26 containing the magnets 27 of a telephone receiver unit, to which current is connected by conductors 28 in the cable 29.

The magnets 27 are adapted to actuate a metallic diaphragm 30 set in the cup 26 at its upper open edge and the cup flange 25 is provided with a plurality of openings 31 communicating with the chamber 12 and cap space 21.

A pair of screws 32 have their threaded portions engaged in the under side of the upper portion of the body 12, the heads of the screws seating against the outer surface of an elongated rectangular bar 33, disposed transversely in the lower part of the body chamber 12 and held in fixed relation in the body 10 by spacing sleeves 34 encircling the bodies of the screws.

A second pair of screws 35 are threaded into the cup flange 25 to extend through the bar 33, their heads being provided with washers 36 on which abut encircling compression springs 37, seated on the outer surface of the bar, the effect being to constantly draw the cup towards the bar and permit of its being adjusted.

A cushioned sub-base 38, of cup shaped design is secured to the body 10 by a clamp screw 39 threaded into the bar 33, this base closing the entrance to the body chamber 12 and providing room for the heads of the screws 35.

In the cap space 21 is disposed an inverted conical paper diaphragm 40, its base being seated against the lower surface of the cap element 15 and its apex, central of the horn 18, in proximity to the metal diaphragm 30.

It will be understood that by rotating the cap or ring dial, constituted by the elements

13 to 17 and 22, the cup 26 and diaphragm 30 carried by it, constituting part of the telephone receiver unit, will be moved towards or from the ring dial and cone diaphragm, causing the sounds produced to vary in pitch from the highest to the lowest obtainable.

This rotation of the ring dial is easily accomplished, due to the raised ribs 17 and 10 is accurately determined by the graduations 23 on the dial, it being noticeable that the dial at all times remains seated on the body, while the telephone receiver unit is held from rotation by the screws 35, but is permitted to move up and down within the body, being guided by the screws.

In the modification shown in Figures 4 and 5, at the center of the diaphragm 40' is a block 41 having a screw threaded stem 42 passing through the diaphragm and engaging in an axial opening in a similar block 43 on its opposite side.

Each of these blocks are cupped at their outer projecting ends to receive contactors, 25 here shown as metal spheres 44, secured by crimping the edges of the cupped recesses to hold them in place.

From the foregoing it will be seen that the spherical contactors are reversible to bring 30 either to bear against the diaphragm 30, and that the cup 26 with the diaphragm 30 may be adjusted towards or from the contactor carrying diaphragm 40' to produce variations in tone.

35 While certain preferred embodiments of this device have been shown and described, it will be understood that changes in the form, arrangements, proportions, sizes and details thereof may be made without departing 40 from the scope of the invention as defined in the appended claims.

Having thus described my invention, what I claim as new and desire to secure by Letters Patent, is:—

45 1. A sound amplifier comprising a hollow support, a dial carrying cap revoluble on said support, said cap having means to engage a horn, a telephone receiver unit in said support, said unit including a diaphragm, 50 a diaphragm carried in said cap, and means to adjust the distance between said diaphragms.

55 2. A sound amplifier comprising a hollow support, a dial carrying cap revoluble on said support, said cap having means to engage a horn, a telephone receiver unit in said support, said unit including a diaphragm, a conical diaphragm in said cap having its apex adjacent the diaphragm of said unit, and means for adjusting said unit relative to the conical diaphragm.

60 3. A sound amplifier comprising a hollow dielectric support, a cap provided with a dial rotatably engaged on said support, resilient means for retaining said cap on said sup-

port, said cap being receptive of a horn, a telephone receiver unit in screw threaded engagement with said cap, means to prevent rotation of said unit, and a conical diaphragm in said cap having its apex adjacent the diaphragm of said unit, said unit, including its diaphragm being adjustable relative to said conical diaphragm by rotating said cap. 70

4. A sound amplifier comprising a hollow 75 dielectric body, a cushion base attached thereto, a revoluble cap on said body, said cap having a graduated dial and an opening to receive a horn, a telephone receiver unit having a flange screw threaded into said cap, a cross bar fixed in said body below said unit, means passing through said bar to prevent rotation of said unit, springs associated with said means to retract said unit, and a conical diaphragm in said cap having its apex directed towards said unit. 80

5. A sound amplifier comprising a hollow 85 dielectric body, a cushion base attached thereto, a revoluble cap on said body, said cap having a graduated dial and an opening to receive a horn, a telephone receiver unit having a flange screw threaded into said cap, said flange being perforate, a cross bar in said body, means for anchoring said bar therein, screws passing through said bar into said unit flange, compression 90 springs interposed between the heads of said screws and said bar, an inverted conical diaphragm fixed in said cap adjacent the diaphragm of said unit, the distance between the diaphragms being adjustable by rotation of said cap, and means on said cap to facilitate its rotation. 95

6. A sound amplifier comprising a hollow 100 body, a telephone receiver unit adjustable therein, a dial carrying cap rotatable on said body having screw threaded engagement with said unit, means on said cap to facilitate its manual rotation, means to prevent rotation of said unit, means to create frictional contact of said cap and body, an inverted paper diaphragm in said cap, the apex of said diaphragm being adjacent the diaphragm of said unit, and a base removable 105 engaged to said body. 110

7. A sound amplifier comprising a hollow 115 body, a telephone receiver unit adjustable therein, a dial carrying cap rotatable on said body, said unit having a perforate 120 flange screw threaded into said cap, said cap having an opening to receive a horn, a cross bar anchored in said body below said unit, means guided by said bar to prevent rotation of said unit, an inverted paper diaphragm in said cap adjacent the diaphragm of said unit, said diaphragms being mutually adjustable by rotation of said cap, a cushion cup base on said body and means to secure said base to said bar. 125

8. A sound amplifier comprising a cham-

- bered base having upper and lower sections, means to engage a horn in the upper section, a telephone receiver unit adjustably engaged in said base, said unit including a metallic diaphragm, a second diaphragm in the upper section of said base, and a spherical contactor carried at the center of the second named diaphragm adjacent the unit carried diaphragm.
- 10 9. A sound amplifier comprising a chambered base having means to engage a horn, a telephone receiver unit adjustably engaged in said base, said unit including a metallic diaphragm, a diaphragm in the upper portion of said base, a block fixed centrally in the last named diaphragm, and a spherical metallic contactor fixed in said block to extend adjacent the unit carried diaphragm.
- 15 10. A sound amplifier comprising a chambered base having means to engage a horn, a telephone receiver unit adjustably engaged in said base, said unit including a metallic
- diaphragm, a second diaphragm in the upper portion of said base, blocks extending oppositely outward from the center of said second diaphragm, and metallic spheres set rigidly in the end extremities of said blocks.
11. In a sound amplifier, the combination with a support, a telephone receiver unit therein, and a rotatable dial, of an inverted conical diaphragm carried by said dial, and means for adjusting said unit relative to said diaphragm.
12. In a sound amplifier, the combination with a sectional support and a telephone receiver unit adjustable therein, of a diaphragm in said support, a spherical contactor fixed on said diaphragm adjacent said unit and positive means to resiliently regulate the distance between said contactor and said unit.

In testimony whereof I have signed my name to this specification.

EARL H. ROLLINSON.
